FLEXIBLE CORD AND RING PUZZLE

David L. Paige, 1682 Newfield Road,
Columbus, Ohio 43209

Filed July 31, 1974, Ser. No. 493,417

Term of patent 14 years

Int. Cl. D21—01

U.S. Cl. D34—15 AG

FIG. 1

FIG. 2

FIG. 3

FIG. 1 is a front elevational view of a flexible cord and ring puzzle embodying my new design.

FIG. 2 is a top plan view thereof.

FIG. 3 is a cross sectional view taken along line 3—3 of FIG. 1.

I claim:

The ornamental design for a flexible cord and ring puzzle, substantially as shown.
